CHANGE MAKER

Application filed July 13, 1928. Serial No. 292,367.

This invention relates to a change-maker, and more particularly to a coin-controlled change-maker of a selective type wherein the coin to be exchanged is deposited in the machine in conformity with a dial on which an index finger, synchronized with change-holders, is employed to indicate what denominations of change coins may be obtained upon operation of the machine.

10 The main object of the invention is the provision of a simple, strong compact and efficient construction of change-maker which may be used in general for mechanically returning various coins in exchange for deposited coins of different denominations.

15 It is within the province of the present invention to make provision for the delivery of a wide variety of different denominations of coins in exchange for various denominations of deposited coins, and further to make provision for quickly and readily varying the character of the change combinations from one particular kind or number of change denomination to another.

20 The particular machine illustrated and described herein has been designed in particular for delivering or returning various change coins in exchange for the deposit of a half-dollar, or of a quarter, or of a dime; and we desire to make it understood that in thus illustrating a particular embodiment of our invention, we have not intended to limit the broader aspects thereof to a machine adapted to change these particular coins only. The 25 machine involves principles of general application which may be variously adapted and modified for delivering or returning change, not only for half-dollars, quarters, and dimes, but also for other denominations of 30 coins now in use, or which may henceforth come into use, as well as for checks, tokens, or other symbols of authenticity.

More specifically considered, the machine of the present embodiment involves a multiplicity of coin-holders, constructed and arranged for quick detachment and interchangeability in order to provide for ready variation of the change combinations; and it also involves a novel arrangement of quick 40 detachable and interchangeable coin ejectors

adapted to have attachments applied thereto or to be structurally varied so as to effect the delivery, on each operation, of the desired number of coins. The coin-holders and coin ejectors are arranged on a rotary structure 55 controlled by a handle. Synchronized with the rotary structure and handle is an index cooperating with a dial showing the various change combinations; this arrangement being such that upon dialing a selected change 60 combination, the coin-holders and ejectors corresponding thereto will be in delivery position, so that upon the deposit of the denomination of coin to be exchanged and upon further operating the handle, the coins indicated by the selected change combination will 65 be delivered.

Another object of the invention is the provision of a change-maker of the character described, capable of utilizing the coin testing 70 device, or a suitable adaptation thereof, constituting the subject matter of a contemporaneously-pending application, to wit, Serial No. 253,410, filed Feb. 10, 1928, by Clifton W. Nixon one of the joint inventors herein.

75 A further object is the provision of a change-maker capable of utilizing as a feature thereof the coin-controlled carrier form of transmission connector constituting the subject matter of a contemporaneously-pending application, to wit, Serial No. 197,075, filed June 7, 1927 by said Clifton W. Nixon. A still further object of the invention is the provision of a change-maker capable of utilizing for the operation of the rotary structure and the transmission connector, the handle operated mechanism disclosed in a contemporaneously-pending application, to wit, Serial No. 197,076, filed June 7, 1927, by said Clifton W. Nixon; 85 or that improved construction thereover which is disclosed in a contemporaneously-pending application, to wit, Serial No. 266,798, filed Apr. 2, 1928, by Louis H. Larsen and Samuel C. McKeown said first named 90 party being the same Louis H. Larsen who is a joint inventor herein. Cross references are hereby made to said applications. The handle operated mechanism herein illustrated by way of example is substantially the same 100

as that disclosed in the application bearing Serial No. 266,798.

Other objects will appear hereinafter.

The invention consists in the details of construction and in the arrangement and combination of parts hereinafter described and claimed.

The invention will be best understood by reference to the accompanying drawings forming a part of this specification, and in which:

Fig. 1 represents a front view of a change-maker produced in accordance with the present invention, the handle being in section;

Fig. 2 represents on a larger scale a vertical section through the machine from front to rear;

Fig. 2a represents one of the dial plates, showing matter in explanation of a change combination;

Fig. 3 represents a plan and section, more or less diagrammatic in character, taken on the line 3—3 of Fig. 2;

Fig. 4 represents a fragmentary view in plan and section, showing the bell crank actuators, the slides connected therewith for receiving and operating the coin ejectors, and showing also how the bases of the coin-holders may be detachably secured to the ring platform;

Fig. 5 represents a top plan view of the coin-controlled carrier form of transmission connector;

Fig. 6 represents a cross section through a coin-holder, the ring platform for the coin-holders, and the guide ring for the coin-ejectors, this view also showing in side elevation a coin-ejector provided with an attachment for ejecting a number of coins at one time;

Fig. 7 represents a cross section taken on the line 7—7 of Fig. 6; and

Fig. 8 represents a perspective view of a coin-holder detached from the ring platform.

The preferred form of construction, as illustrated in the accompanying drawings by way of example, comprises a casing or cabinet 10 of any suitable type or construction for housing the various mechanisms and devices, the casing being provided exteriorly as shown in Fig. 1 with a face panel 11 having therein a circular aperture 12 in open communication with the upper end of a vertical slot 13. The purpose of the circular aperture is to provide for the rotation of an operating handle 14, while the purpose of the slot 13 is to provide for the pivoting movement of said handle and at the same time to serve as a guide for preventing any turning of the handle during its pivoting movement. In the upper end of the face panel 11 are provided the coin deposit slots 15, 16 and 17, designed in the present instance to receive, respectively, a dime, a quarter and a half-dollar, to be exchanged for coins of smaller denominations. Arranged adjacent the face panel 11

is a dial 18 provided with a suitable index finger 19. At the lower end of the casing or cabinet is a delivery receptacle 20 for receiving the discharged change coins such delivery receptacle being open exteriorly of the casing where ready access may be had thereto by the patrons of the machine.

Within the casing or cabinet is provided a suitable rotary device, by preference in the form of a spider structure 21 supporting thereon for rotation therewith a ring platform 22 provided at its inner circumference with an internal gear 23. A rotary axis shaft 24, mounted at its lower end upon the casing base 25 by means of a suitable anti-friction structure 26 and near its upper end in framing 27, supports the spider structure and receives rotary movement therefrom. The top surface of the ring platform has an annular shoulder 28 separating an inner annular surface 29 from an outer annular surface 30 at a lower elevation. Upon the lower surface 30 are mounted in close compact arrangement a circular series of coin-holders 31, while upon the higher surface 29 are mounted coin-ejectors 32, there being in the present embodiment one coin-ejector for each coin-holder. According to an important feature of the present invention, the coin-holders and coin-ejectors are individually detachable, so as to be replaced or interchanged as desired in order to make provision for a great variety of change combinations.

The coin-holders contain the change to be dispensed in exchange for the coin inserted through the coin deposit slots; and they differ in size as desired or as may be necessary in order to provide the various change combinations. While the coin-holders may have different diameters in order to accommodate different denominations of coins, they are nevertheless provided with base plates 33 having the same form and area, the entire arrangement and lay out in this regard being such that standardized base plates will serve for use in connection with coin-holders of the largest diameters intended to be employed. The standardized base plates are herein shown as provided with suitable countersunk openings 34 adapted to receive headed screws 35 or equivalent means for detachably securing them in place upon the lower surface 30. Columns of coins, placed within the coin-holders, are supported upon the top surface of the base plates 33; and the thickness of the standardized base plates is such that the coin-ejectors 32, slide transversely of the ring platform upon the higher surface 29 thereof, will enter rear openings 36 in the coin-holders and discharge the lowermost coin or coins, as the case may be, out through the front openings 37 of the coin-holders. The coin-ejectors are slidably maintained in place upon the higher surface 29 of the ring platform by means of guides 38 detachably secured by 130

screws 39 or equivalent means upon said higher surface 29. Preferably and as shown the coin-ejectors and their guides are inter-shouldered as shown at 40 in Fig. 7. In this 5 way, there is provided for each coin-holder an individual coin-ejector; both the coin-holder and coin-ejector being mounted for quick detachment so that they may be readily interchanged or replaced as conditions 10 of use require. It will be apparent that the rear and front openings 36 and 37 of the coin-holders may be made to provide for the discharge of more than one coin at each thrusting operation of the coin-ejector. 15 Where more than one coin is to be discharged at one time, the accompanying ejector is provided as shown in Fig. 6 with an attachment 41 or equivalent means adapted to push out the number of coins in excess of one, for 20 which it is intended.

Means in the form of a stationary guide ring 42 are provided to maintain the coin-ejectors in proper position for receiving the thrusting impulse when along with their 25 coin-holders they are in station or delivery position, and further to maintain them against inward or outward movements during the time they are carried by the rotary structure through the circuit to station or 30 delivery position. Said guide ring 42 has an annular groove 43 therein for receiving suitable pins 44 depending from the ejectors near the inner ends thereof, said pins 44, when the ejectors are in station or delivery 35 position for receiving a thrusting impulse, being adapted to escape through suitable slots 45 in guide ring.

As the coin-ejectors are brought into station or delivery position for the ejection of 40 coins from the coin-holders into a delivery chute 46 which leads to the delivery receptacle 20, suitable pins 47 upwardly projecting from the coin-ejectors enter transverse grooves 48 provided for the purpose in the 45 lower faces of heads 49 provided at the outer ends of the slide means through which the thrusting movements are imparted to the coin-ejectors. In the present exemplification, the slide means are shown to comprise three 50 slide members 50, 51 and 52 mounted for individual reciprocation in a platform 53 held by frame parts 54 depending from an overhead structure 55, said platform being thus supported within the circle of coin-holders. Each of the slide members 50, 51 55 and 52 has its head 49, as best shown in Fig. 4, provided with a transverse groove 48 which is curved in agreement with the curvature of the grooves 43 in the guide ring 42. In 60 the present instance, the head 49 on the slide member 52 has a shoulder 56 engaging behind a shoulder 57 on the head of slide member 51; this arrangement being such that the slide member 51 will be thrust with the 65 thrusting movement of slide member 52,

while said slide member 51 is at all times free to be moved individually without effecting the movement of the slide member 52.

The slide members 50, 51 and 52 operatively embrace, respectively, bell crank actuators 58, 59 and 60, mounted on a common pivot shaft 61 to be partially rotated thereon. These bell crank actuators constitute power receiving means and the upper ends of their long arms, which pass through the slide members, are provided with hooks 62 adapted to be engaged with cooperating hooks carried by the coin-controlled units on the transmission connector to be presently described. The short arm of each bell crank actuator 70 engages under a lift frame 63 including as part thereof a pair of side members 64 swingably mounted at their front ends upon the pivot shaft 61 and converging towards their rear parallel ends 65 which lie at opposite sides 75 of the shaft 24 upon a collar 66 thereon. Suitable spring means 67, attached at 68 to the lift frame and at 69 to the casing base 25, resiliently maintain the lift frame, bell 80 crank actuators and connected slide members 85 in proper position for actuation, and further promptly repositions these parts as well as any coin-ejectors coupled or interengaged with the heads of the slide members, after 90 each actuation thereof. By this arrangement, each bell crank actuator, upon being operated toward the casing front 70, raises the lift frame 63 and a sleeve 71 resting upon the parallel ends 65, said sleeve being loosely 95 mounted on the axis shaft 24.

It will be apparent that the operation of the bell crank actuator 60 toward the casing front 70 will impart thrusting movement to both of the slide members 52 and 51 and hence to the coin-ejectors coupled with the heads thereof; while the operation of bell crank actuator 59 will impart thrusting movement to slide member 51 only, it being noted in the present instance that the head on slide member 51 is of sufficient expance 100 to engage and operate two coin-ejectors at one time. The operation of bell crank actuator 58 effects the operation of its connected slide member 50 and the coin-ejector coupled with the head thereof. During the 105 turning of the rotary structure, pins 47 of the coin-ejectors can pass freely through the grooves 48 in the heads of the slide members, and said heads prevent the pins 44 from escaping through the openings 45 in the 110 guide ring. The guide ring 42 is supported by suitable brackets 72 depending from the framing 27, by a bracket 73 depending from an arm 74 attached to said framing 27, and by horizontal brackets 75 projecting from the depending sides 54.

We have observed that the slide members 50 and 52 each command one coin-ejector, while the slide member 51 commands two coin-ejectors. In the present embodiment,

therefore, the total number of coin-holders, which is forty, is divided into ten sets or change combinations, each of which consists of four coin-holders. Now the arrangement of parts, as herein illustrated, is such that each time the operating handle 14, which is of rectangular form in cross section, is turned into position to enter the slot 13, a set of four coin-holders will be in station or delivery position before the slide members; and in order precisely to position the rotary structure when a set of coin-holders is in station or delivery position, diametrically opposite spring urged rollers 76 engage simultaneously in arcuate seats or notches 77 provided in the outer circumferential edge of the ring platform 22. The rollers 76 enter and leave each seat or notch 77 over an inwardly sloping edge 78. By the concerted action of the spring urged rollers 76 on the sloping edges 78, the rotary structure is precisely self-centered before the handle can be moved into slot 13, that is to say, a set of coin-jetectors is in station or delivery position for the pins 44 to escape through the outlet slots 45 in the guide ring when the handle, which is the generator of power for operating the bell crank actuators, is in position for pivoting movement in the slot 13. Said rollers 76 are carried by plungers 79 slidably mounted in open ended cylinders 80. Coiled springs 81 within the cylinders urge the plungers outwardly. The cylinders 80 are carried by suitable brackets 82 secured to appropriate frame parts. In this connection it is to be noted that because of the provision of the seats 77 and spring urged rollers 76, the rotary structure cannot be rotated too rapidly.

In the present instance, we show three sets 40 *a* of like change combinations, which are indicated on the dial 18 by three dial plates *a'*, all distinguished by bearing green indications of color. Two sets *b* of like change combinations are distinguished by dial plates 45 *b'*. Further, three sets *c* are distinguished by dial plates *c'* in red, while two sets *d* are shown by dial plates *d'* in blue. By preference, the dial plates are rectangular in form; and as illustrated in Fig. 2a they are divided 50 into vertical columns 83, 84 and 85 showing, respectively, the denominations of coins delivered by the machine in exchange for the deposit of a half-dollar, quarter, and dime.

At this point, in order that the preferred embodiment of our change-maker as illustrated in the accompanying drawings by way of example, may be readily understood it is deemed best to describe briefly the adaptation and arrangement herein of the handle 55 operated mechanism and of the coin-controlled carrier form of transmission connector, to which, respectively, cross reference has been made hereinbefore. The handle 14, for the handle controlled mechanism, is mounted to have two distinct movements,

viz., rotary movement and pivoting movement. The rear portion of the handle is mounted for rotation in and extends through, a bearing block 86 supported solely by a fulcrum pin 87 for rocking movement of frame 70 88 secured to a cross piece 89. By turning the handle, rotary movement is imparted to the spider structure 21 through sliding connections 90, short shaft 91, bevel gears 92, shaft 93, spur gears 94, shaft 95, and spur gear 96 which is in driving engagement with internal gear 23 on the spider structure. The pivoting movement of the handle consists in downward and upward strokes whereby the bearing block is rocked on its fulcrum pin, the downward stroke or depression of the handle being provided in order to move a pull-bar 97, which is pivoted at 98 to the frame 88, upwardly and rearwardly on an arc. This operation is accomplished 80 through bell crank lever 99, which is pivoted at 100 to frame 88, and a link 101 having one end thereof pivoted to said bell crank lever and the other end thereof pivoted to the draw-bar 97. Said bell crank lever 99 has a lost motion connection at 102 with the bearing block 86. A weighted arm 103 having one end thereof fixed to the fulcrum pin 87 normally keeps the handle in elevated position within the circular aperture 12. With this construction, the handle when within the circular aperture is freely rotatable for turning the spider structure in either direction; and the preferred gearing ratio is such that one complete revolution of the handle will turn the spider structure a distance sufficient to move one set of coin-holders from station position and the next adjacent set into station position.

The coin-controlled carrier, which serves as a transmission connector between the draw-bar 97 and the bell crank actuators, comprises as shown in Fig. 5, three elongated strips 104, 105 and 106 connected by cross pieces 107 and 108 which are furnished with shoes 109 having sliding fit between upper and lower rails 110 and 111. Coiled pull springs 112 connect a cross piece 113 fixed to the strips 104 and 106, with rigid projections 114 adjacent the casing front 70, whereby the carrier structure is retracted against an abutment block 115. With each of these strips 104, 105 and 106, is associated a coin-controlled unit including a head 116 and a slide 117 forming a coin-space. The coin-spaces differ in size to accommodate the denominations of coins to be exchanged. Thus, with strip 104 is shown a coin-space 117 adapted to receive a dime; with strip 105 is shown a coin-space 118 adapted to receive a quarter; and with strip 106 is shown a coin-space 119 adapted to receive a half-dollar. The slides 117 have movement relatively to their heads 116, being provided with pins 120 110 115 120 125 130 135 140 145 150 155 160 165 170 175 180 185 190 195 200 205 210 215 220 225 230 235 240 245 122, connecting the pins 120 with pins 123 fixed to the strips, the slides are drawn toward their heads to clamp the coins in the coin-spaces. The slides carry laterally projecting pins 124 which cooperate with stop pins 125 depending from the frame plate 55 to adjust the slides and make the coin-spaces of coin receiving size as the carrier is retracted to the abutment block. As the carrier is advanced from the abutment block, the tensioned slides clamp any coins reposing in the coin-spaces. To the strip 105 is pivoted at 126 a pull-bar 127 suitably hooked to be engaged by the draw-bar 97 for the advancement of the spring tensioned carrier away from the abutment block.

When, in operation, a slide 117 clamps a coin against its cooperating head 116, it is thereby rendered effective upon the carrier being drawn to extreme position from the abutment block to engage the hooked end of a pivoted catch bar 128 with the hooked end 62 of the corresponding bell crank actuator, so that upon the retiring movement of the carrier toward the abutment block, the engaged bell crank actuator will also be drawn forwardly to effect a discharge of the change. Where there is no coin in the coin space, a slide will not be connected with its bell crank actuator, its catch-bar 128 falling short of engagement with the hooked end 62 thereof, because of the lost motion of the slide occasioned by the disengagement of the pin 124 from the stop pin 125. Just prior to the return of the carrier to its position of rest against the abutment block and after the coins have been discharged, the engaged bell crank actuator is released for its movement to starting position because of the engagement of a cam portion 129 on the catch-bar 128 with a trip device 130. To put the returning movement of a carrier toward the abutment block positively beyond the control of the handle and under the control of the retractile springs 112, a kick-up pin 131 which rests upon the sleeve 71 to rise therewith, engages the pull-bar 127 and disconnects the same completely from the draw-bar 97.

The index finger 19 on the dial 18 is operated in synchronism with the spider structure by any suitable means, that shown comprising a shaft 132 to which the index finger is attached, co-operating bevel gears 133, and shaft 134 which carries a bevel gear 135 in engagement with a similar gear 136 on the axis shaft 24.

From the coin deposit slots 15, 16 and 17 the deposited coins are led to the respective coin-spaces 117, 118 and 119 through the instrumentality of a coin testing device 137, preferably of the type fully disclosed in the application above referred to.

The operation of the carrier may be regulated and steadied through the employment

of a piston 138 in an air cylinder 139, said piston being suitably connected by a rocking arm 140 with the cross plate 113 of the carrier.

In operation, the handle 14 is turned until the index finger 19 points to the dial plate showing the selection of change desired. With the selection dialed and with the handle in position to be depressed, the corresponding set of coin-holders will be in station or delivery position. Thereupon, upon depositing a dime, a quarter, or a half-dollar, and upon depressing the handle, the exact change will be delivered into the delivery receptacle 20. In the embodiment shown in Figs. 3 and 4 each set of coin-holders *a* comprises a column of quarters, a column of dimes and two columns of nickels, arranged so that when this set is in station or delivery position the column of quarters will come opposite slide member 52, the column of dimes and one column of nickels opposite slide member 51, and the remaining column of nickels opposite slide member 50, it being noted that from the column of nickels opposite slide member 51, three nickels are discharged at one operation while for the column of nickels opposite slide member 50 two nickels are discharged at one operation. If a half-dollar be deposited, there will be discharged in accordance with the dial plate shown in Fig. 2*a*, one quarter, one dime and three nickels. If a quarter be deposited, one dime and three nickels will be discharged. If a dime be deposited, two nickels will be discharged. In Fig. 3, we have disclosed under the various sets of coin-holders marked *a*, *b*, *c* and *d*, various desirable change combinations. By means of this system or arrangement, any change combination that may be required for the coins now in common use, may be provided.

While we have illustrated and described the preferred form of construction for carrying our invention into effect, this is capable of variation and modification without departing from the spirit of the invention. We, therefore, do not wish to be limited to the precise details of construction set forth but desire to avail ourselves of such variations and modifications as come within the scope of the appended claims.

Having thus described our invention, what we claim is:

1. A change-maker comprising means for holding different denominations of coins to be dispensed, an operating element, a device with retractile means arranged to be cooperatively connected by said operating element for movement against said retractile means, said device being operable by a coin to be exchanged for controlling the ejection at one time of two or more coins having a combined value equal to the value of the coin to be exchanged, and means for discon-

necting said device from said operating element to place the former under the control of its retractile means.

2. In a change-maker, consisting of a rotary structure and a transmission connector with coin-controlled devices adapted to be operated by different denominations of coins, actuators with connected slides arranged to be operated by said devices through the power of said connector, a multiplicity of coin-holders on said structure provided with individual ejectors adapted selectively to be brought into position to be moved to and fro by said slides.

15 3. In a change-maker, consisting of a rotary structure and a transmission connector with coin-controlled devices adapted to be operated by different denominations of coins, actuators with connected slides arranged to be operated in one direction by said devices through the power of said connector, a multiplicity of coin-holders on said structure provided with individual ejectors adapted selectively to be brought into position to be moved to and fro by said slides, and means effective for repositioning said actuators and connected slides.

4. In a change-maker, consisting of a rotary structure and a transmission connector with coin-controlled devices adapted to be operated by different denominations of coins, actuators with connected slides arranged to be operated by said devices through the power of said connector, sets of coin-holders on said structure provided with ejectors adapted selectively to be brought into position to be operated by said slides, a dial synchronized to turn with said structure and bearing indications identifying said sets of coin-holders.

40 5. In a change-maker, in combination, a movable structure, a transmission connector with coin-controlled devices, actuators operable by said devices, slides operable by said actuators, a handle having one movement for moving said structure and another movement for moving said connector to effect the operation of said actuators and slides, and a multiplicity of coin-holders associated with said structure and having ejectors adapted to be brought into coupling relation with said slides, said coin-holders with their ejectors being interchangeable to vary their relationship individually with respect to said slides.

45 6. In a change-maker, in combination, a rotary structure, a transmission connector with coin-controlled devices, actuators operable by said devices, slides controlled by said actuators, a ring platform on said structure provided with equi-spaced notches, spring cushioned rollers turning on said platform and into and out of said notches, said rollers being located to center said structure in relation to said slides, a multiplicity of coin-holders mounted on said platform, and ejec-

tors for said coin-holders adapted selectively to be brought into coupling relation with said slides.

7. In a change-maker, in combination, a movable structure, a transmission connector with coin-controlled devices, retractile springs acting on said connector, actuators operable by said devices, slides operable by said actuators, means for moving said structure, means for moving said connector against the urge of its springs, means for transferring the control of said connector from its moving means to its springs as a coin-controlled unit partially operates an actuator, and a multiplicity of coin-holders mounted on said structure and having ejectors adapted selectively to be brought into coupling relation with said slides.

15 8. A change-maker having a plurality of slides, a handle, coin-controlled means for operating said slides, means for connecting said handle with said coin-controlled means, a multiplicity of coin-holders movable in a path to be brought selectively into relation with said slides, and ejectors controlling the discharge of coins from the coin-holders, arranged to be engaged and operated by said slides.

9. A change-maker having a plurality of slides, a handle, coin-controlled means for operating said slides, means for connecting said handle with said coin-controlled means, a multiplicity of coin-holders, ejectors associated with said coin-holders, and guide means for directing said ejectors into and out of cooperative coupling relation with said slides.

10 10. A change-maker having a slide, a handle, coin-controlled means for operating said slide, means for connecting said handle with said coin-controlled means, a movable structure with a multiplicity of coin-holders, ejectors for said coin-holders arranged on said structure for movement to and fro and adapted to be cooperatively coupled with said slide, and guide means for directing said ejectors into and out of cooperative coupling relation with said slide.

11 11. In a change-maker, embodying coin-controlled means and a structure with a series of coin-holders, a handle, means for connecting said handle with said coin-controlled means, ejectors associated with said coin-holders, an actuator depending for its operation upon the operation of said coin-controlled means, and a plurality of slides operable by said actuator and arranged to establish and disestablish an operative connection with selected ones of the ejectors.

12 12. A change-maker having a plurality of coin-controlled devices, each capable of receiving a different denomination of coin to be exchanged, a transmission connector carrying the coin-controlled devices, a corresponding plurality of actuators engageable

by the coin-controlled devices and operable thereby through the power of said connector, a corresponding plurality of slides operable by the actuators, a multiplicity of coin-holders with individual ejectors, and means for establishing and disestablishing an operative connection between said slides and selected ones of the ejectors.

5 In testimony whereof, we have signed our names to this specification.

10 LOUIS H. LARSEN.
CLIFTON W. NIXON.
